US00D708057S

(12) **United States Design Patent**
Hansen

(10) **Patent No.:** **US D708,057 S**
(45) **Date of Patent:** **** Jul. 1, 2014**

(54) **BEVERAGE CARTRIDGE**

(75) Inventor: **Nick Andrew Hansen**, Banbury (GB)

(73) Assignee: **Kraft Foods R & D, Inc.**, Deerfield, IL (US)

(**) Term: **14 Years**

(21) Appl. No.: **29/431,718**

(22) Filed: **Sep. 10, 2012**

(51) **LOC (10) Cl.** 09-03

(52) **U.S. Cl.**

USPC **D9/429**

(58) **Field of Classification Search**

(57) **CLAIM**

The ornamental design for a beverage cartridge, as shown and described.

DESCRIPTION

FIG. 1 is a top and front side perspective view of a first embodiment of a beverage cartridge showing my new design; FIG. 2 is a left side elevation view thereof;

FIG. 3 is a bottom and front side perspective view thereof;

FIG. 4 is bottom plan view thereof;

FIG. 5 is a front side elevation view thereof;

FIG. 6 is top plan view thereof;

FIG. 7 is a right side elevation view thereof;

FIG. 8 is a rear side elevation view thereof;

FIG. 9 is a top and rear side perspective view of a second embodiment of a beverage cartridge showing my new design;

FIG. 10 is a left side elevation view thereof;

FIG. 11 is a bottom and rear side perspective view thereof;

FIG. 12 is bottom plan view thereof;

FIG. 13 is a front side elevation view thereof;

FIG. 14 is top plan view thereof;

FIG. 15 is a right side elevation view thereof;

FIG. 16 is a rear side elevation view thereof;

FIG. 17 is a top and front side perspective view of a third embodiment of a beverage cartridge showing my new design;

FIG. 18 is a left side elevation view thereof;

FIG. 19 is a bottom and rear side perspective view thereof;

FIG. 20 is bottom plan view thereof;

FIG. 21 is a front side elevation view thereof;

FIG. 22 is top plan view thereof;

FIG. 23 is a right side elevation view thereof; and,

FIG. 24 is a rear side elevation view thereof.

Broken line disclosures in the figures are for illustrative purposes only and form no part of the claimed design.

1 Claim, 12 Drawing Sheets
